UNITED STATES PATENT OFFICE.

JAMES S. LANG, OF BOSTON, MASSACHUSETTS.

INCANDESCENT IGNITER FOR GAS-ENGINES.

No. 896,398.

Specification of Letters Patent. Patented Aug. 18, 1908.

Application filed June 9, 1905. Serial No. 264,443.

To all whom it may concern:

Be it known that I, JAMES S. LANG, of Boston, in the county of Suffolk and State of Massachusetts, a citizen of the United States, have invented a new and useful Improvement in Incandescent Igniters for Gas-Engines, of which the following is a full, clear, and exact description, reference being had to the accompanying drawings, forming a part of this specification, in explaining its nature.

My invention relates to an igniter or means of ignition like that shown and described in Letters Patent, No. 727,158, granted to me May 5, 1903. As described in said patent, the means of ignition comprises an igniting device contained in the exhaust passage to the combustion chamber of the engine. This device is kept hot by the repeated discharges of the exhaust expelled through this passage and is adapted by its heat or incandescence to ignite the gaseous charges as they are successively formed in the combustion chamber.

According to the operation of the usual form of explosion engine, the gaseous charge is drawn into the combustion chamber and the exploded residue or products of combustion are expelled therefrom by the operation of the piston, the gas being drawn in by a stroke of the piston in one direction and the exploded residue expelled by its stroke in another or reverse direction. The piston acts to force practically all the exploded residue from the combustion chamber or cylinder in which it works, but leaves some of the exploded residue in the exhaust passage, or an amount at any rate sufficient to act as a mantle enveloping the igniter contained in said passage and preventing it from too soon igniting the new gaseous charge as it is formed in the combustion chamber. As the new gaseous charge is compressed by the stroke of the piston it acts also to compress that portion of the exploded residue left in the exhaust passage until the piston has arrived at the full limit of its stroke and the gaseous charge is fully compressed ready to be exploded, when the exploded residue left in the exhaust passage is so far compressed that the end of the igniter will be exposed to the new gaseous charge and its heat will then explode it.

In order that the igniter may explode the gaseous charge at just the proper moment, it is necessary for it to occupy a relatively correct position in the exhaust passage with

relation to the combustion chamber, and, as described in my said Letters Patent, I have arranged for this by having the igniter movable in said passage towards or from the combustion chamber, so that it may be moved or adjusted to a position where it will ignite the gaseous charge at the proper time. Now if the amount of gas drawn into the combustion chamber were always the same, then the degree of its compression and that of the exploded residue left in the exhaust passage would likewise be the same, so that after the igniter had once been moved to a normally correct position it would not be necessary to change its position in order to properly ignite the gaseous charges as they were successively formed in the combustion chamber. The fact is, however, that the amount of gas or explosive mixture varies depending upon the will of the operator, a greater amount of gas being let into the combustion chamber when it is desired to obtain a heavy explosion and a less amount of gas for a lighter explosion, depending upon the amount of power to be obtained. On account of this variance the degree of gas compression in the combustion chamber and the degree of compression of the exploded residue in the exhaust passage varies also, being greater when more gas is fed into the combustion chamber and less when less gas is let into the same. It accordingly becomes necessary to vary the position of the igniter in the exhaust passage; in other words, to move it to a position nearer the combustion chamber when a less amount of gas is let into the same, or to a position farther away from the combustion chamber when more gas is fed into said chamber, in order that as the exploded residue left in said passage is compressed to a lesser or greater degree, as before explained, the igniter may be exposed in proper position to ignite the gaseous charge at the proper moment of its full compression.

It is accordingly the special object of my invention to provide means by which this adjustment of the igniter may be obtained.

It is the further object of my invention to provide a new form of igniter itself.

All of these features can best be seen and understood by reference to the drawings, in which—

Figure 1 shows mainly in vertical section a portion of a gas explosion engine fitted with my improved means. Fig. 2 shows an enlarged detail thereof to which reference will

hereinafter be made, and Fig. 3 shows the improved form of igniter in perspective. Fig. 4 shows a detail of the check and spindle.

Referring to the drawings:—A represents a portion of the cylinder of a gas explosion engine forming the combustion chamber *a* in which is a piston *B*. The gas is fed into the combustion chamber through the inlet passage *a'* and the exploded residue is expelled through the outlet or exhaust passage *a''*. Both these passages are valve-controlled in the usual manner. The valve *a³* controls the inlet passage and the valve *a⁴* the outlet passage.

15 In the outlet or exhaust passage there is arranged an igniter *C* which is adapted to ignite, as before described, the gaseous charges successively formed in the combustion chamber. The igniter is arranged upon the end of 20 the igniter rod *c* which extends through the wall forming the exhaust passage in the direction in which the igniter moves in said passage.

For controlling the gas inlet passage, or for 25 graduating the amount of gas which can be let or drawn into the combustion chamber, I have arranged in said passage a gate or check *D*. This is in the nature of a damper arranged upon a spindle *d* on which the damper 30 may be turned from an open to a closed or partially closed position and consequently a full or lesser amount of gas let or allowed to pass into the combustion chamber. The spindle *d* is arranged to turn in the wall forming 35 the inlet passage and at one end extends to project through the same by a projecting end or gudgeon *d'*. This projecting end *d'* of the spindle has affixed to it a lever *E* which 40 operates the damper. The lever *E* has projecting beyond the point where it makes attachment with the spindle an operating arm *e* and in order to permit of an adjustable lengthening of this arm (for a purpose which 45 will hereinafter be explained), the projecting end *d'* of the spindle where it connects with the lever is made square so as to fit within the slot *e¹* formed in said lever and be secured by a nut *d²*. It is, of course, obvious that by 50 means of this slot the lever may be moved longitudinally upon the projecting end of the spindle and its operating arm *e* lengthened or shortened so relatively changing the distance or arc of its movement upon turning the lever. Pivoted to the end of the arm *e* of the 55 lever is a rod *d³* which connects with the end of the rod *c* carrying the igniter, so that as the lever is turned to operate the gate or

check *D* it will also, through the connecting rod, move the igniter in the exhaust passage toward or from the combustion chamber. 60 Now the arrangement of the gate or check *D* with respect to the lever is such that as the lever is turned in a direction to move the igniter in the exhaust passage farther away from the combustion chamber it will also 65 open or move wider open the gate or valve controlling the gas inlet passage, or vice versa, when it moves the igniter towards or nearer the combustion chamber, it also tends to close the valve. Thus the wider the 70 valve *D* is opened and the more the gas which is allowed to pass into the combustion chamber, the farther away the igniter will be moved from the combustion chamber in order that its exposure for ignition of the gaseous charge may be delayed to the time when the charge is fully compressed; so also, the 75 more the valve *D* is closed and the less the amount of gas allowed to pass into the combustion chamber, with a consequent lesser 80 degree of compression, the more will the igniter be moved towards the combustion chamber in order that it may be exposed to the gaseous charge and ignite it at the moment of its full compression. 85

By lengthening or shortening the operating arm *e* of the lever, which may be done as above described, the arm when the lever is turned is made to pass through a longer or shorter arc of movement, and the effect is for 90 the igniter to be moved in the exhaust passage a longer or shorter distance relatively to the movement of the valve or damper *D* controlling the inlet passage, so that by properly adjusting the length of this operating lever 95 arm the damper and igniter may be simultaneously moved in proper ratio.

Having thus fully described my invention, I claim and desire to secure by Letters Patent of the United States:—

100 In an engine of the character specified having a combustion chamber, a gas inlet and exhaust passage, an igniter contained in said exhaust passage, a damper or check in said gas inlet passage, a spindle on which said 105 damper or check is mounted, a lever fulcrumed upon said spindle and fixed thereto, and means connecting said lever with said igniter.

JAMES S. LANG.
